UNITED STATES PATENT OFFICE.

VICTOR MELLBERG, OF NEWARK, NEW JERSEY.

CAPSULE CLOSING AND PRINTING MACHINE.

No. 820,724.

Specification of Letters Patent.

Patented May 15, 1906.

Application filed April 6, 1905. Serial No. 254,154.

To all whom it may concern:

Be it known that I, VICTOR MELLBERG, a citizen of the United States, residing in the city of Newark, county of Essex, and State of New Jersey, have invented certain new and useful Improvements in Capsule Closing and Printing Machines; and I do hereby declare the following specification, taken in connection with the accompanying drawings, forming a part of the same, to be a full, clear, and exact description thereof.

The invention relates to machines for closing the open ends of flexible tubes or capsules such as are used for paints, pastes of various kinds, and medicinal preparations by folding over the open end of such capsules after they have been filled with such preparations, and thereby sealing the same. After the end has been folded over the flat portion of the fold may receive a printed inscription through the mechanism which forms a part of this invention.

The object of my invention is to provide an automatic mechanism for closing the open ends of such capsules and to do the same much more rapidly and with far less expenditure of hand-labor.

A further object is to provide a capsule-closing machine with a printing attachment whereby the closed capsule may be properly labeled, or, if desired, the advertising-card of the user may be printed across the folded end of the capsule. I may add here that the printing or stamping of names or card across the folded end has the further advantage of more closely sealing the capsule, inasmuch as the parts are pressed more closely together and therefore more firmly united.

In carrying out my invention I make use of mechanism substantially as illustrated in the accompanying drawings, in which—

Figure 1 illustrates a plan view of the machine, showing the same in position to receive a capsule in the holder preparatory to closing the end thereof. Fig. 2 is a side elevation of the same, illustrating certain parts thereof in detail. Figs. 3 and 4 illustrate elevations of the opposite side of the machine, showing in detail the printing attachment.

Fig. 5 illustrates a gage or support more fully hereinafter described. Fig. 6 illustrates a section on line 6 6 of Fig. 7, and Fig. 7 illustrates a sectional view on line 7 7 of Fig. 6. Figs. 8, 9, 10, 11, 12, 13 illustrate diagrammatically the several positions assumed by operative parts of the mechanism during

the process of closing the end of the capsule. Figs. 14, 15, 16, and 17 illustrate, respectively, the capsule during the various steps of forming the parts thereon. Figs. 18 and 19 illustrate two corresponding steps in the process of closing the capsule by making what I term a "triple" fold.

The machine consists of the following parts:

A is a frame provided with the flaring base-flange A' and having the side members A² and the forwardly-projecting members A³, said forwardly-projecting members A³ being connected by an integral cross member A⁴. The back portion of the frame extends over at the upper part to form the hood A⁵. The forwardly-projecting members A³ are provided with the horizontal guide-slots a, as shown particularly in the side elevation. Journaled in the upper portion of the frame and beneath the hood A⁵ is the shaft C, said shaft projecting laterally of the vertical side of the machine, as shown in Fig. 7. Mounted upon the ends of this shaft and secured thereto by means of the set-screws b is the sectional cam-lever B. This cam-lever is shown in Figs. 1 and 7 as made in two parts secured together by means of the screw b² in the handle thereof. The two sections of the cam-lever are reversed counterparts of each other—that is, they have the same contour, with the exception that the one is right-handed and the other is left. The sections of this cam-lever are provided with the slotted cams B². The two cam-slots b³ and b⁴ are provided in each section. The cam-slot b³ is substantially circular in cross-section, the center of the arc upon which it is struck being considerably eccentric to the shaft C. Mounted in the slots a of the forward extension A³ of the frame is the horizontally-sliding plunger a³, (clearly shown in Fig. 1,) having the laterally-extending arms a⁵, which take into the slot b³ of the cam-lever. The forward portion of this plunger is reduced in thickness, as shown at a⁴. The end portions of the extensions a⁵ are provided with anti-friction-rollers a⁶ for the purpose of reducing the friction of the extensions a⁵ with the cam-slot b³. Secured beneath and to the forwardly-extending portion of the hood A⁵ by means of the screws, as shown, is the anvil a² in alignment with the plunger a³, both plunger and the anvil being made of case-hardened steel.

D is a folder and consists of a cylindrical

shaft mounted to oscillate in the frame A, the bearings thereof being in substantial alinement with the slots a . The ends of the shaft D project laterally of the frame some distance, as shown in Fig. 1, and are provided with crank-arms D^2 , said crank-arms being secured to the extremities of the shaft by means of the set-screws d . The outer ends of the arms are provided with crank-pins which 10 take into the cam-slots b^4 of the cam-lever B^2 , antifriction devices being provided for the purpose of reducing the friction to a minimum. These antifriction devices consist merely of flange-rollers mounted upon the 15 crank-pins, the reduced portion thereof extending into the cam-slots, as clearly shown in the drawings. That portion of the folder D comprised between the sides A^2 of the frame is cut away, so as to leave its cross-section substantially as shown in Figs. 6, 8, 9, &c. It will be noted that the cam-slots b^4 20 are irregular in contour, having the upper portion, as illustrated in Fig. 6, substantially straight, while the lower portion is curved backward, being substantially an involute of the shaft C. Mounted between the said members A^2 of the frame, as shown in Fig. 2, is a small shaft E, carrying upon its right-hand exterior end the operating-ratchet E' , 25 said ratchet being provided with an even number of teeth. In the present case six of such teeth are shown. Pivoted just above said ratchet is the stop-pawl F^5 , which engages the teeth of the ratchet E' . Mounted upon the inner side of right-hand section of 30 the cam-lever is the spring-pawl G, said pawl operating during the movement of the handle B to rotate the shaft E through the ratchet E' . On the shaft E, between the 35 side members A^2 of the frame, is secured the lobed cam E^2 , there being just half as many lobes to this cam as there are teeth in the ratchet E' .

In the lower portion of the frame A is journaled the horizontal shaft F. Secured to the shaft F by means of the set-screw f' is the sleeve F' . Projecting upwardly from the sleeve F' is the arm F^2 , carrying at its upper extremity the roller F^3 , said roller engaging 40 the lobes of the cam E^2 . Projecting forwardly from the sleeve F' are the two arms F^4 , carrying at their outer ends the adjustable pivots f^2 . Suspended from said pivots is the saddle G, which has the greater portion 45 of its weight to the rear of the pivots f^2 , so that its lower portion has a tendency to swing forward. It is made of the general contour illustrated in Fig. 6, having the seat G' at the bottom, and is designed to carry the socket 50 H for the reception of the capsule. When the socket H is in position, as shown in Figs. 6 and 7, it has a tendency to fall rearwardly, and the upper portion thereof contacts with one of the lobes of the lobe-cam E^2 . The 55 socket H and saddle G may tilt forward, how-

ever, so that the inserted capsule may be readily removed by hand.

I have provided the forward portion of the socket with a slot h , in which is inserted the adjusting-screw h' for the purpose of adjusting the seat h^2 within the socket to various positions, as indicated in Fig. 7, so as to provide for capsules of different sizes. When the seat h^2 is properly adjusted for the capsule to be closed, the upper edge or open end of the 75 capsule will project upwardly between and slightly above the plunger a^3 and anvil a^2 .

Secured to the shaft C at its left-hand end is the eccentric C', which in turn carries the eccentric-strap C² and connecting-rod C³, the 80 lower end of which is pivoted to the cross-head I, said cross-head being guided by the posts I', as shown clearly in Figs. 3 and 4. Between said posts I' is located the socket I², in which is located a line of steel type I³. 85

Projecting laterally from the left-hand side of the base of the machine, as shown in Fig. 7, is the gage-rod K, carrying an adjustable yoke K', secured to said rod by means of the set-screw k in any desired position. This 90 yoke K' is of the general contour illustrated in Fig. 5, having a series of slots k^2 of suitable size to receive the covering-cap of the capsule, as illustrated in Fig. 7. The yoke K' is adjusted along the rod K and angularly upon 95 the same to receive the capsule L, so that the folded end of the same will project toward the machine and lie upon the upper face of the type-bar I³ and just beneath the cross-head I. 100

The operation of the machine is as follows: With the handle B in the position indicated in Fig. 3, it will be noted that the plunger a^3 is at the forward end of the slot a . The filled capsule with its end open is then inserted in 105 the socket H, the seat having been adjusted to the proper height, so that the upper edge of the capsule will project somewhat above the plunger a^3 and the folder D. Upon bringing the handle B forward into the position illustrated in Fig. 6 the plunger a^3 will be forced rearward, as shown, compressing the upper edge of the capsule, and simultaneously the folder D is rotated through action of the cam-slot b^4 and cranks into the position shown in Fig. 6, so as to fold the upper edge of the capsule at right angles to the length of the capsule, as shown in Fig. 15. Further forward movement of the handle B will 110 retract the plunger a^3 , and simultaneously the folder D is rotated into the position shown in Fig. 10—that is, against the face of the anvil or abutment—so as to fold the upper edge of the capsule into the position shown in Fig. 16. The lever B is then in the position 115 shown in Fig. 4. Upon the return stroke of the lever B to its initial position it will be noted that the plunger a^3 will again be brought forward into the position shown in Fig. 6, and the folder D simultaneously 120

130

tates backwardly out of the path of the plunger, said plunger during this stroke compressing the lightly-folded upper end of the capsule, and the further rearward stroke of the handle B will retract the plunger a^3 and rotate the folder D into the position shown in Fig. 11. Simultaneously with the rearward stroke of the handle B the pawl G will engage one of the teeth of the ratchet E', carrying with it the lobed cam E³, thereby tilting the lever F² backward, and through its connection with the arm F⁴ and saddle G the socket H is elevated slightly to carry the capsule upwardly for the second fold. The handle B is then brought forward as before, the operation being identical with that just described for the first fold when the second fold, as shown in Fig. 17, is produced, and upon the return of the handle B to this initial or rear position, as shown in Fig. 3, the socket H, containing the capsule, is tilted forward and the capsule removed and placed in the position shown in Fig. 7, resting with its capped end in one of the notches or slots K² in the yoke K, with the folded end resting upon the type-bar I². The machine is now ready to receive another capsule in the saddle G. Upon the repetition of the operation just described to fold the second capsule the cam C' is brought into operation, thereby depressing the cross-head I upon the folded end of the first capsule, thereby depressing such folded end upon the type-bar I³ and printing the desired inscription thereon. These two operations are repeated for each capsule.

In order to produce the requisite pressure for printing upon the folded end of the capsule, I have found it necessary to provide some adjustment for the stroke of the cross-head I. A convenient method for doing this is to limit the forward stroke of the lever B, so that the eccentric may be stopped when the desired degree of compression is reached. In order to limit the stroke of the handle B, I insert in the forward side of the plunger a^3 an adjusting-screw L, which in the position shown in Fig. 3 and also in Fig. 1 will contact with the cross-piece A⁴ and when properly adjusted limit the stroke of the handle B, and with it the throw of the eccentric C'. It will be noted that this screw L may be screwed out or in to vary the length of the stroke of the plunger a^3 , and thereby the forward stroke of the handle B.

The pawl F⁵ is for the purpose of preventing any backward movement of the ratchet E when the roller F³ rests upon any one of the lobes of the cam E'. When the roller F³ rests between any two of these lobes, accidental rotation of the cam E² will be prevented.

When it is desired to produce the triple fold, (shown in Fig. 19,) it is only necessary to elevate the adjustable seat h² a little higher than for the double fold. (Shown in Fig. 17.) The first operation of the machine

will then produce the fold shown in Fig. 18 and the second that shown in Fig. 19.

In the use of this machine I have found that the resulting closed capsule possesses additional advantages not secured by hand-work. In forming the folds as described a portion of the contents of the capsule becomes imprisoned right at the angle of the bend in each of the folds, as shown at x, Figs. 16 70 17, 18, and 19, thus forming a perfect seal for 75 the end of the capsule thus closed.

It will thus be seen that for each complete stroke of the handle B and its return to its initial position the plunger a^3 will advance twice toward the anvil—first, to compress the 80 open end of the capsule and fold the same over at right angles, and, second, to press or pinch the part which is made by the folder D. The second stroke of the handle B produces the same results, with the exception that the 85 capsule has been elevated slightly to form the second fold, the second advance of the plunger a^3 compressing and finishing the closing of the capsule so far as such closing is necessary. 90

In order to prevent shocks due to careless handling of the machine, I insert rubber cushions y in the cam-slots b³.

At first glance it might be thought that the folder D when being rotated to form the first 95 fold would interfere with the forward edge of the plunger a^3 . To avoid such interference, I make the cam-slots b⁴ concentric with the shaft C between their straight portions and their involute portions. The straight and 100 involute portions of these slots thus produce, in combination with the concentric portions thereof, a varying oscillating velocity of the folder. It will thus be seen that for a portion of the stroke of the handle B the folder D remains stationary, and this at the time when the plunger a^3 is in proximity to the anvil a². 105 Thus all interference of parts is avoided.

I have provided the holes M in the base of the machine in order to secure the same to 110 any fixed support whereby the machine may be rendered stable.

Having thus described my invention, what I claim is—

1. In a capsule-closing machine, the combination of a rigid abutment or anvil, a plunger in alinement therewith, a folder, means for oscillating said folder, and means for moving said plunger against and retracting the same from said abutment, and thereafter oscillating said folder against the face of said abutment or anvil. 115 120

2. In a capsule-closing machine, the combination of a rigid abutment or anvil, a reciprocating plunger, an oscillating folder, and means for simultaneously reciprocating said plunger and oscillating said folder, against the face of said abutment or anvil. 125

3. In a capsule-closing machine, the combination of a rigid abutment or anvil, a re- 130

- reciprocating plunger, an oscillating folder, a lever provided with means for actuating said plunger and a means for actuating said folder, to cause the same to press against the face of said abutment or anvil.
4. In a capsule-closing machine, the combination of an abutment or anvil, a reciprocating plunger, and oscillating folder, means for advancing and retracting said plunger, and means for simultaneously oscillating said folder, against the face of said abutment or anvil.
5. In a capsule-closing machine, the combination of an abutment or anvil, a reciprocating plunger, and oscillating folder, means for advancing and retracting said plunger and means for oscillating said folder at a varying velocity during the advance and retraction of said plunger.
6. In a capsule-closing machine, the combination of an abutment or anvil, a plunger, a folder, means for advancing and retracting said plunger, means for moving said folder forward a portion of its stroke during the advance of the plunger, and then holding said folder stationary during a portion of the reverse movement of the plunger and thereafter continuing the forward movement of the folder during the remainder of the rearward stroke of said plunger.
7. In a capsule-closing machine, the combination of an abutment or anvil, a plunger, guides for said plunger, means for advancing and retracting said plunger along said guides, a folder, means for oscillating said folder during the advance of the plunger, a capsule-holder, means for elevating said holder during each alternate rearward stroke of said plunger.
8. In a capsule-closing machine, the combination of an abutment or anvil, a plunger, a folder, an oscillating lever, a cam upon said lever for actuating said plunger to advance and retract the same toward and from said abutment, a second cam upon said lever for actuating said folder simultaneously with the movement of said plunger.
9. In a capsule-closing machine, the combination of a frame or support, an abutment rigidly secured upon said frame, a plunger mounted to slide in guides upon said frame, a folder journaled in said frame, a lever journaled upon said frame, a cam upon said lever for actuating said plunger, a second cam upon said lever for actuating said folder, a capsule-holder supported by said frame, connection between said holder and said lever, whereby said holder is alternately elevated and lowered.
10. In a capsule closing and printing machine, the combination of means for closing the open end of a capsule, with means for printing an inscription upon the closed end of said capsule.
11. In a capsule closing and printing machine, the combination with means for folding and sealing the end of a capsule, to form a flat printing-surface, of mechanism actuated by the operative parts of said means for printing an inscription upon the flat printing surface of said capsule.
12. In a capsule closing and printing machine, the combination with means for closing and sealing the end of a capsule, to form a flat printing-surface, of an eccentric and strap secured to the shaft of the closing and sealing means, a guided cross-head connected to said strap, and a line of type fixed in the path of said cross-head, whereby the operation of the machine to close and seal one capsule will print an inscription upon the printing-surface of a second capsule.
13. In a capsule-closing machine the combination with means for closing a capsule, of means for folding over and compressing the closed end of said capsule, and means for alternately raising and lowering said capsule whereby a plurality of folds may be formed in the closed end thereof.
14. In a capsule-closing machine, the combination of a frame, a shaft journaled in the upper portion of said frame, a sectional lever secured to the ends of said shaft, pairs of cams in said lever, a guided plunger having lateral studs in engagement with and operated by one pair of said cams, a folder journaled in said frame in substantial alinement with said plunger, cranks upon the ends of said folder in engagement with and operated by the second pair of cams, a capsule-holder pivotally supported in said frame, and means operated by said sectional lever for alternately elevating and lowering said capsule-holder.
15. In a capsule closing and printing machine, the combination of a frame, a shaft journaled in the upper portion of said frame, a sectional lever secured to the ends of said shaft, pairs of cams in said lever, a guided plunger having lateral studs in engagement with and operated by one pair of said cams, a folder journaled in said frame in substantial alinement with said plunger, cranks upon the ends of said folder in engagement with and operated by the second pair of cams, a capsule-holder pivotally supported in said frame, and means operated by said sectional lever for alternately elevating and lowering said capsule-holder.

This specification signed and witnessed this 1st day of April, 1905.

VICTOR MELLBERG.
